UNITED STATES PATENT OFFICE.

WILLIAM L. JACOBY, OF LARCHMONT, NEW YORK, ASSIGNOR TO THE AMERICAN DISTRICT TELEGRAPH COMPANY, A CORPORATION OF NEW JERSEY.

THERMOSTATIC CIRCUIT-CONTROLLER.

1,097,640.

Specification of Letters Patent. Patented May 26, 1914.

Application filed February 12, 1913. Serial No. 747,894.

To all whom it may concern:

Be it known that I, WILLIAM L. JACOBY, a citizen of the United States, and a resident of Larchmont, county of Westchester, 5 in the State of New York, have invented certain new and useful Improvements in Thermostatic Circuit-Controllers, of which the following is a specification, reference being had to the accompanying drawings, 10 which form a part hereof.

This invention relates to thermostatic circuit controllers especially adapted for use in electric fire alarm systems.

The invention seeks to provide an efficient and reliable device, simple, compact and durable in structure, convenient to install and inspect and which shall be protected from interference arising from accumulations of dust or moisture or arising 20 from tampering.

The invention is shown in its preferred and modified forms in the accompanying drawings, in which,

Figure 1 is a plan view of the device, in 25 its preferred form, with the cover removed but indicated in dotted lines. Fig. 2 is a sectional elevation on the line 2—2 of Fig. 1, with the cover in place. Fig. 3 is a sectional elevation on the line 3—3 of Fig. 2 30 showing a detail of the structure as shown in Figs. 1 and 2. Figs. 4 and 5 are side elevations, partly in section, of two modified arrangements.

Referring now to the structure, as shown 35 in Figs. 1, 2 and 3 of the drawings, 1 is an enameled cast iron case. Firmly secured to the bottom wall 2 inside the case and insulated therefrom is a brass plate 3 held in position by the screws 4, 5 and 6. Passing 40 through a threaded hole in this plate is an adjustable screw contact post 7 which provides one contact for the circuit controller. Passing through a hole in the bottom wall of the case and directly opposite the post 7 is a contact stud 8 which provides the 45 other contact of the circuit controller. This stud is rigidly fixed to a thermal member carried by the bracket 9 projecting from the wall 2 outside of the case. The movement of the thermal member, due to expansion and contraction, imparts a corresponding movement to the stud 8 to and from the post 7, thereby closing the alarm circuit

when the contacts meet and opening the alarm circuit when the contacts separate. 55 In order that the contacts may be arranged to open and close at any desired predetermined temperature, the threads of the post 7 are cut to a predetermined number to the inch and the post has provisions whereby 60 it may be accurately adjusted with reference to the stud 8. In the present instance, these provisions comprise a graduated plate 10 secured to the upper end of the post 7 and a corresponding pointer 11 fixed to the 65 plate 3.

The thermal member preferably consists of two thermal elements 12 and 13 which have a differential movement and thereby impart movement to the stud 8 fixed to the 70 element 13. The element 12 consists of a metal strip which is angular in cross section and is secured at its middle portion to the bracket 9 by screws 14. The thermal element 13 consists of a metal strip initially 75 bowed and brazed or otherwise securely fixed to the ends of the element 12. As thus arranged, any expansion of the element 12 tends to straighten the element 13 and retard the inward movement of the stud 8. 80 The quantity of heat absorbed by either of the elements 12 or 13 in a given time is a function of the surface area of the element, the nature of the surface, that is, whether smooth or rough, black or white, etc., the 85 temperature difference between it and the outer air, and the quantity of air passed over the surface, that is, the amount of draft. The temperature rise of either element in a given time is a function of the quantity of 90 heat it absorbs, its mass and its specific heat. When, therefore, a draft of hot air passes over the elements 12 and 13, assuming them to be of the same metal, both rise in temperature and expand. The element 13 has less 95 mass in proportion to its exterior surface than the element 12 and it, therefore, assumes the temperature of the surrounding air more rapidly and expands to a greater degree. This causes the element 13 to become more bowed and advances the stud 8 into contact with post 7 and produces an alarm for a quick temperature rise. During 10 this operation, there is not sufficient time for the element 12 to more than expand slightly and its retarding effect upon the inward

movement of the element 13 is, therefore, negligible. When, however, the rise in temperature of the surrounding air is slow, the temperature of the element 12 lags behind that of the element 13 a less amount, while for a still slower temperature rise, they both would assume the temperature of the outside air at almost the same time. Under such slower rise in temperature the element 13 would expand and tend to bow or move inward as before, but would be kept from any substantial movement by the expansion of the element 12 which would force the ends of the element 13 apart, thereby preventing the element 13 from any substantial movement inward and from imparting such an inward movement to the stud 8. Thus, the thermal member is capable of bringing the stud 8 and post 7 into contact and thereby closing the alarm circuit when the surrounding air has a sudden rise in temperature, such as that produced by a fire near the thermal member, but does not close the alarm circuit when the rise in temperature is slow, such as results from normal conditions. It is frequently desired, however, that the alarm circuit should be closed when the temperature of the surrounding air, by a slow rise, has reached a predetermined maximum. In order that this may be accomplished without complicating the structure, the elements 12 and 13 are preferably made of different materials, the former having a lower coefficient of expansion than the latter, and the elements 12 and 13 being so proportioned as to their mass and superficial area that the expansion of element 13 is very slightly in excess of that which can be neutralized by the expansion of the element 12. As thus arranged, when the temperature rises there is continually a slight inward movement of the stud 8, so that, at the predetermined maximum temperature, the circuit is closed even though the element 12, as well as the element 13, has reached this temperature and the rise in temperature has been slow. Thus, the alarm closes when the temperature has reached the danger point whether the rise has been slow or fast.

In order that the screw post 7 may be securely locked in any position to which it may be adjusted, the plate 3 is provided with a portion 15 which is separated from the adjoining portions of the plate by the slots 16 and 17 and is thus made movable. Half of the threaded hole through which the post 7 passes is formed in one edge of this portion 15.

18 is a set screw which works in the plate 3 against one edge of the movable portion 15 and operates to clamp it against the post 7 and thereby lock the post securely in place.

19 and 20 are binding posts fixed to and in electrical connection with the plate 3 and projecting outside of the case on opposite

sides and insulated from the case. 21 and 22 are binding posts which are secured to the outside of the case on opposite sides. These four posts are preferably made to look alike, as shown in the drawings. When the device is connected in circuit, the wires of one polarity are connected to the posts 19 and 20 and the wires of the opposite polarity are connected to the posts 21 and 22. Thus, the current of one polarity passes through the plate 3, entering at one side of the case and emerging at the opposite side thereof, and the current of the opposite polarity passes through the case itself, entering at one side of the case and emerging at the opposite side thereof. The alarm circuit is closed when the contacts 7 and 8 touch and thereby form a cross connection between the positive and negative wires. If any unauthorized person attempts to disconnect the device from its circuit, he would be most likely to connect, as the first step of his operation, two of the posts or wires on the same side of the case, such as the posts 19 and 21 or their connected conductors. This would produce a cross between the positive and negative wires and close the alarm circuit and lead to detection of such tampering.

The case is cast open on its inner side and, when installed, this open side is closed by a tight fitting block of insulation 23 secured to the case by bolts 24 which pass through lugs 25 on the case. The nuts which hold these bolts rest in holes countersunk on the outer side of the block 23, the holes being filled above the nuts with an insulating cement 26.

The entire device is secured to a wall or ceiling by screws 27 which pass through holes in the block 23.

28 is a perforated guard plate to protect the thermal member. It extends across the case outside of the thermal member.

It will be seen that the case is substantially dust and moisture proof, that the device is simple, compact and durable in structure, is protected from unauthorized interference and may be readily installed in position, on wall or ceiling, as a unitary structure. It will also be seen that its contacts may be adjusted, with great convenience, to open and close the alarm circuit at the desired temperature simply by turning one element, namely, the post 7.

In Figs. 4 and 5, 29 is a metal yoke adapted to be secured to a wall or ceiling by means of screws 30 and provided with binding posts 31 for the circuit wires of positive polarity. 32 is a bracket extending from the yoke and supporting the thermal member 33 which is similar to the thermal member shown in Figs. 1, 2 and 3. The bracket 32 is in electrical connection with the yoke 29 and the thermal member. 34 and 35 are insulated

ing blocks secured to the yoke by means of screws 36. 37 is a metal plate secured to the insulating blocks 34 and 35 by means of screws 38. 39 is an adjustable screw contact post provided with a graduated dial 40 and passing through the plate 37. 41 is a fixed pointer for the dial. 42 is a tubular member of insulating material secured to the plate 37 by screws 43 and surrounding the inner end of the post 39. 44 are the binding posts for the negative circuit wires and secured to the plate 37.

In Fig. 4 the thermal member 33 carries a fixed contact stud 45 which performs the office of a contact in association with the contact post 39. It enters within the tubular member 42 from a hole in the yoke. The tubular member 42 is closed at one end by the plate 37 and at the other end by the yoke 29. Thus, the yoke, the tubular member 42 and the plate 37 provide an inclosing case for the contacts to protect the contacts from dust and moisture. When these contacts touch, they establish a cross between the positive and negative sides of the circuit in the same way as is done in the structure shown in Figs. 1, 2 and 3.

Fig. 5 differs from Fig. 4 in that the contact which coöperates with the post 39 is carried by the yoke within the tubular member 42 and the stud carried by the thermal member is not itself an electrical contact, although it is a contact maker, as is the stud in the other figures of the drawings. In Fig. 5 the thermal member 33 carries a stud 46, the upper end of which is made of insulation and bears against a spring contact 47 mechanically and electrically secured to the yoke 29. When the stud 46 moves inward, it pushes contact 47 against contact post 39 thereby establishing a cross between the positive and negative wires.

While the invention is herein shown in its preferred form and two of its possible modifications, it will be understood that various other changes may be made without departing from the scope of the invention.

What I claim is:

1. The combination with a contact device, of a thermostat for operating said device and comprising a plurality of elements having different physical characteristics whereby the contact operating movement of the thermostat under the influence of relatively slow elevations of temperature below a definite degree is prevented, and having other different characteristics whereby the operation of the contact device is effected for elevations in temperature above said definite degree irrespective of the rate of change.

2. A thermostatic couple consisting of elements of different material and having different mass, and a connection between said elements whereby the variation in expansion

due to differences in mass neutralizes the effect of expansion resulting from relatively slow elevations of temperature below a critical point, while permitting the variation in expansion due to differences in material to be effective for all elevations of temperature above the critical point.

3. A thermostat consisting of a bar of material of considerable mass, and a relatively thin strip of material secured at its ends to the bar and being bowed with respect thereto, the material composing the bar and strip having different coefficients of expansion, the bar and strip being so proportioned as to their mass and superficial area that the expansion of one is slightly in excess of that which can be neutralized by the expansion of the other.

4. In a thermostatic circuit controller, the combination of a case, a stationary contact within the case, a thermal member having a differential movement, said thermal member comprising two strips rigidly connected at their ends, said strips being so proportioned as to their mass and superficial area that the expansion of one is slightly in excess of that which can be neutralized by the expansion of the other, a bracket fixed exteriorly to the case to which the thermal member is secured at its middle portion, and a contact stud secured to said thermal member and passing through a wall of the case into coacting relation with said stationary contact, said contact stud having a movement resulting from the differential movement of said thermal member.

5. The combination with a case having two pairs of terminals, each pair being situated at opposite sides and near one extremity of said case, the diagonally opposite terminals of the two pairs being conductively connected, and a thermostatic controller within the case adapted to short circuit the pairs of terminals.

6. In a thermostatic circuit controller, the combination of a metal case; a conducting plate fixed within the case and insulated therefrom; a contact post carried by said plate; a thermal member fixed to the case on the outside thereof and in electrical connection therewith; a contact stud carried by said thermal member and passing through a wall of the case into coacting relation with said contact post; binding posts secured to the outside of the case on opposite sides thereof; and binding posts connecting with said conducting plate and projecting outside of the case on opposite sides and insulated therefrom.

7. In a thermostatic circuit controller, the combination of a metal case; a conducting plate fixed within the case and insulated therefrom, said plate being provided with a threaded hole and having a movable portion containing part of said hole; a set screw

carried by the plate for operating said movable portion; an adjustable screw contact post passing through said hole and adapted to be locked in place by said movable portion of the plate; a thermal member fixed to the case on the outside thereof and in electrical connection therewith; and a contact stud carried by said thermal member

and passing through a wall of the case into coacting relation with said contact post.

This specification signed and witnessed this eleventh day of February, A. D., 1913.
